UNITED STATES PATENT OFFICE

GEORGE W. TROMMLITZ, OF DENVER, COLORADO, ASSIGNOR, BY DIRECT AND MESNE ASSIGNMENTS, TO THE TROMMLITZ VOTE REGISTER COMPANY, OF SAME PLACE.

VOTING-MACHINE AND BOOTH.

SPECIFICATION forming part of Letters Patent No. 638,683, dated December 5, 1899.

Application filed September 20, 1898. Serial No. 691,411. (No model.)

To all whom it may concern:

Be it known that I, GEORGE W. TROMMLITZ, a citizen of the United States of America, residing at Denver, in the county of Arapahoe and State of Colorado, have invented certain new and useful Improvements in Voting-Machines and Booths Therefor; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in voting-machines and booths therefor, my object being to provide an apparatus of this class which shall be simple in construction, economical in cost, reliable, durable, and efficient in use; and to these ends the invention consists of the features, arrangements, and combinations hereinafter described and claimed, all of which will be fully understood by reference to the accompanying drawings, in which is illustrated an embodiment thereof.

In the drawings, Figure 1 is a perspective view of the booth and machine, the front portion of the latter being exposed. Fig. 2 is a fragmentary front view of the machine shown on a larger scale. Fig. 3 is a fragmentary rear view of the same. Fig. 4 is a fragmentary rear view of the mechanism inclosed by the box or case, the rear wall and the counting-registers attached thereto being removed.

Fig. 5 is a section taken on the line X X, Fig. 4. Fig. 6 is a vertical section taken through the case, showing an individual push-key connected with the lever for actuating the counter-registering mechanism, the parts being shown in their normal position. Fig. 7 is a similar view showing the same parts in the actuated position. Figs. 8 and 9 show in plan view the outer slides in the positions corresponding, respectively, with the positions of the parts in Figs. 6 and 7. Figs. 10 and 11 are similar views of the inner or auxiliary slides. Fig. 12 illustrates both the individual and straight-ticket push-keys and their connections shown in their normal position. Fig. 13 shows the

positions of the same parts when actuated by a straight-ticket push-key. Fig. 14 is a fragmentary plan view of the rock-shaft carrying dogs which actuate the bell-crank levers during the operation of voting straight tickets. Fig. 15 is an elevation of the slide-supporting guide-bridge. Fig. 16 is a section taken through the upper part of the case and illustrating the straight-ticket push-key lever. Fig. 17 shows the slide-stop in two positions—that is to say, in elevation and plan view. Fig. 18 is a section taken on the line y y, Fig. 2. Fig. 19 is a section taken on the line z z, Fig. 18. Fig. 20 illustrates the mechanism attached to the exit-door of the booth. Fig. 21 is a side elevation of the slide adapted to move in a guide attached to the exit-door of the booth. Fig. 22 is a section taken on the line w w, Fig. 21. Fig. 23 is a detail view of the rod connected with the slide-releasing mechanism. This rod is actuated by the mechanism mounted on the exit-door of the booth. Fig. 24 is a section taken on the line v v, Fig. 20, looking downward. Fig. 25 is a fragmentary view of the individual-push-key locking-slides, showing also the lever with which they are connected for operating the straight-ticket-push-key locking-slide. Fig. 26 is a rear view similar to Fig. 4, illustrating the slide for the straight-ticket push-keys and the slides for the individual push-keys, also the lever connecting the one slide with the other slides, the locking positions of the slides and the corresponding position of the lever being indicated by dotted lines.

Similar reference characters indicating corresponding parts in the views, let the numeral 5 designate the booth, provided with an entrance-door 6 and an exit-door 7. The door 7 opens outwardly and actuates devices for releasing the push-keys from the locking action of the slides, all as hereinafter set forth.

The voting-machine is located within the booth. In Fig. 1 the front portion of the case is exposed.

In this specification the side of the machine provided with the push-keys is termed the "front" and the opposite side the "rear."

The mechanism of the voting-machine

proper will be first described, after which the slide-releasing mechanism and its connection with the exit-door will be explained.

The mechanism of the machine is inclosed 5 within a suitable case. The front and rear sides of this case are detachable. The outer front plate 8 is provided with slots 8^a of sufficient width to expose the names of the candidates on tickets 12, which are inserted 10 between the outer plate and the inner plate 9. These slots are closed by plates 10, composed of glass or other suitable transparent material. The outer plate 13 of the rear side of the case is also slotted to expose the names 15 on tickets, which are placed between the plate 13 and the inner plate 14. These tickets correspond with the tickets placed on the front side of the machine. The plates 13 and 14 are further provided with openings 13^a and 20 14^a, in one of which is set a transparent plate 15. These openings are located opposite the count-registering devices 16, which are of ordinary construction. These registering devices are attached to the inner 25 surface of the plate 14 and are utilized in counting the votes. The number of these registering devices corresponds with the number of the candidates on all the tickets. There is one of these devices located adjacent the name 30 of each candidate on each ticket, and the number of votes cast for any candidate is indicated by the register and may be read through the openings in the rear wall of the case, through which the figures of the register are seen. The mechanism for actuating these counting registers, and through the instrumentality of which the voting is accomplished, will now be described. This mechanism allows the voter to vote the straight 35 ticket by pressing a suitable push-key placed adjacent the head of the ticket or to vote for individual candidates by pressing the push-keys located adjacent the names of the candidates.

40 The front wall of the case is provided with two sets of push-keys—that is to say, those actuated in voting separately individual candidates and referred to in this specification as "individual" push-keys and those actuated 45 in voting straight tickets and referred to herein as "straight-ticket" push-keys. The individual push-keys are designated in the drawings by the numeral 17 and the straight-ticket push-keys by the numeral 18. These push- 50 keys 17 and 18 are provided with notches 17^a and 18^a, adapted to be engaged by locking-slides 19 and 19^a, as hereinafter fully explained. Both sets of these push-keys are also provided with wedge-shaped inner extre- 55 mities, as shown at 17^c and 18^c, respectively, for a purpose hereinafter explained. To the inner extremity of each push-key 17 is pivotally attached one extremity of a link 20, whose opposite extremity is movably con- 60 nected with one arm 21^c of a bell-crank lever 21, fulcrumed on a rod 22, suitably supported on the inner front plate of the case. The op-

posite arm 21^a of this lever is adapted to engage a pressure-foot 16^a of the registering device 16. As the push-key is pressed this foot 70 is forced inwardly and the registering mechanism actuated. (See Fig. 7.) The foot is returned to its normal position through the instrumentality of a spring 16^c of the counting-register. (See Fig. 21.) Each lever 21 is 75 provided with a third arm 21^d, which projects outwardly or in the direction opposite the arm 21^a to engagement with a stop 23, made fast to a slide 19. Hence as the lever is actuated by the push-key the arm 21^d of the lever 80 forces the slide 19 into the notch 17^a of the push-key. As shown in the drawings, the slides 19 are provided with openings to allow the push-keys to pass therethrough. Each slide 19 is of sufficient length to coöperate 85 with all the individual push-keys located in the same horizontal plane—that is to say, all the push-keys adjacent the names of all the candidates for the same office on the various tickets. Hence as any one of these individual 90 push-keys is pressed and the slide 19 actuated the said slide enters the notch 17^a of the actuating push-key and moves to a position in the rear of a shoulder 17^d, formed on the inner extremity of each push-key in the same 95 plane or series, thus locking all of the corresponding push-keys from movement until the slide is returned to its normal position. The slide also when in this position prevents the return movement of the actuating push-key. 100 Each slide 19 is held in place and guided during its movement by blocks 24, made fast to the plate 9 in the case. These blocks are provided with recesses 24^c, (see Fig. 15,) adjacent the plate 9, through which the slide 105 passes. The slides 19 are all connected with a screw 55, Fig. 4. They are all provided with angle-arms 19^c, Fig. 25, except the slide in line with the screw. Each slide is slotted, as shown at 19^d, to allow it to move freely on 110 the connecting-screw. Each slide 19 is provided at the extremity remote from the screw with a tooth or projection 19^e, Fig. 5, which as the slide is actuated by the lever 21 is engaged and held in the adjusted position by a 115 dog 25, movably mounted on a shaft 26 and provided with an arm 27. These arms are engaged by leaf-springs 27^a. All of the slides 19 are simultaneously released from the dogs 25 by mechanism which will now be described. 120 Loosely mounted on the shaft 26 are two arms 28, which support a rod 29, to which is attached one extremity of a rod 30. This last-named rod is actuated by a dog 31, Fig. 20, mounted on a vertical shaft 32, journaled on 125 the booth adjacent the exit-door 7. (See Fig. 1.) As the shaft is turned the dog 31 engages the vertical face of a lug 33 on the rod 30 and actuates the latter, which in turn moves the rod 29 to engagement with all the arms 27 of the dogs 25, thus actuating the dogs 25 sufficiently to disengage them from the teeth 19^c of the slides, thus releasing the slides, which are returned to their original or normal posi-

tion through the instrumentality of the pressure-feet 16^a of the registers 16, which force the levers 21 to their normal position or that shown in Figs. 3 and 10 of the drawings. The 5 levers in turn force the push-keys outwardly, the slides 19 being returned to their normal position by the inclined faces of the notches 18^a.

To operate the elements just described, the shaft 32, mounted on the booth, as aforesaid, 10 is turned by a bar 34, (see Fig. 20,) one extremity of which is fast on the shaft 32, while the other extremity is provided with a cross-head 35, which slides in a retaining-guide 36, fast on the exit-door. As this door is opened 15 outwardly the bar 34 is swung sufficiently to actuate the shaft 32 for the purpose stated. The door and all the working parts connected therewith are returned to their normal position through the instrumentality of suitable 20 automatic door-closing mechanism 37, (see Fig. 1,) which may be of any suitable construction, and therefore is not described in detail. Hence all the push-keys 17 are locked at their inward limit of movement when once pressed 25 in the act of voting for a candidate until the voter leaves the booth by the exit-door. At the same time all the push-keys adjacent the names of the other candidates for the same office are locked against inward movement 30 as fast as the voter presses the push-keys in voting for one set of candidates, and these keys cannot be again moved until the voter has left the booth by the exit-door, as heretofore stated. This construction and arrangement 35 prevents the voter from voting more than once for the same candidate and also from voting for more than one candidate for the same office.

To vote straight tickets, the push-keys 18 40 are actuated. These are located at the heads of the tickets adjacent the emblems. (See Fig. 2.) To facilitate the operation of these push-keys, since considerable pressure is required, levers 57 are employed. Each of these 45 levers is fulcrumed on a post 38, supported on the front wall of the case, and engages the push-key 18 at a point between the fulcrum and the lever extremity. Each key 18 is connected at its inner extremity with a link 50 20 of substantially the same construction as the links 20 connected with the push-keys 17. The inner extremity of each of these links 20 is pivotally connected with a crank-arm 39, whose opposite extremity is made 55 fast to the rock-shaft 40, upon which are secured a number of dogs 41, which correspond with the number of candidates on the tickets. These dogs are so located that when the rock-shaft 40 is actuated by the pressure of the 60 push-key 18 each dog 41 engages the arm 21^c of the lever 21 and actuates the lever sufficiently to register a vote for each candidate on the ticket in the same manner as explained when describing the action of the individual 65 push-keys in connection with the same levers. The locking-slide 19^a for the straight-ticket push-keys is substantially of the same con-

struction, so far as its body portion is concerned, as the slides 19. To the extremity of the slide 19^a, corresponding with the slotted 70 extremities of the slides 19, is pivotally connected one extremity of a lever 42, which is fulcrumed at 43 on the plate 9, its opposite extremity being connected with the screw 55, which passes through the slots 19^d of all 75 the slides 19; but is not fastened to the plate 9. It is evident that all the slides 19, as well as the push-keys 17 adjacent the names of all the candidates on the straight ticket voted, are actuated by the pressure 80 of a straight-ticket push-key. As the slides 19 are moved in the direction indicated by arrow a, (see Figs. 4 and 26,) the lever 42 is turned on its fulcrum, moving the slide 19^a in the opposite direction or that indicated 85 by arrow c. The push-keys 18 are provided with bevel-faced notches 18^a, located on the opposite sides of the push-keys from the corresponding notches in the push-keys 17. The slide 19^a enters the notch 18^a of the push-key 18 actuated and at the same time passes to the rear of shoulders 18^d, formed on the inner extremities of the other straight-ticket 90 push-keys. Hence when any straight-ticket push-key is pressed all the other push-keys 95 are locked against movement until the voter leaves the booth by the exit-door, and the slides are released, as heretofore explained. As soon as the individual-push-key locking-slides 19 are released the action of the feet 100 16^a on the levers 21 forces the individual push-keys 17 outwardly. During this movement the action of the beveled faces 17^a of the keys 17 forces the said slides to the right, (referring to Figs. 2 and 19,) leaving the lever 42 free 105 to move from the dotted-line position shown in Fig. 19 to the full-line position in the same figure. The straight-ticket-push-key locking-slide 19^a is then free to move toward the left, which it does in the following manner: 110 As the levers 21 are acted on by the feet 16^a of the counting-registers and forced outwardly, returning the individual push-keys to their normal position, the arms 21^c of these levers act on the dogs 41 of the rock-shaft 40 and 115 impart a partial rotation to the said shaft, whereby the lever-arm 39, fast on the shaft 40, acts on the link 21 of the straight-ticket push-key 18 and thrusts the latter outwardly to its normal position. As this key 18 moves outwardly the action of its beveled face 18^a on the slide 19^a, together with the influence of the spring 44 on the lever 42, serves to throw the slide 19^a toward the left, releasing all of 120 the straight-ticket push-keys. (See full lines 125 in Fig. 26.)

To prevent the actuation of two push-keys simultaneously by the voter, I employ auxiliary locking-slides 45. (Shown in detail in Figs. 10 and 11.) These slides are divided 130 into sections 45^a, which are supported by the blocks 24, the latter being provided with recesses 24^c, (see Fig. 15,) which said sections engage. They are held in place by a bridge-

plate 24^d, attached to the top of the block. The sections 45^a have semicircular extremities 45^e. When in their normal position, these extremities of any two adjacent slides 5 engage each other and form circular openings 46. Each terminal 45^e is provided with an inwardly-projecting tongue 45^d, which protrudes into the opening 46 and lies in the path of the wedge-shaped terminal or extremity 10 17^e or 18^e, as the case may be, of the push-key. Hence as any push-key is thrust inwardly it forces the two terminals 45^e apart, (see Fig. 11,) thus moving all the other sections of the same slide sufficiently to bring the tongues 15 45^d of the sections into a position to form stops against the inward movement of any other push-key in the line of the slide. The end sections of the slide 45 are only allowed sufficient movement to permit the complete 20 operation of a single push-key at one and the same time. This necessary but limited expansion of the slide 45 is permitted by means of bow-shaped leaf-springs 47, mounted on stops 48, made fast to the plate 9. These 25 springs are engaged by the ends of the terminal sections of the slide and normally hold the sections in contact to form a practically continuous slide 45. When a single push-key is pressed inwardly, these springs yield 30 sufficiently to allow the slide to expand just enough to permit the complete operation of the single push-key, but no more. These auxiliary locking-slides are employed with both individual and straight-ticket push-keys, 35 and their construction is substantially the same in both cases. These slides for the individual push-keys are provided with openings 45^e, through which the projections 21^d of the levers 21 pass. These openings are 40 sufficiently large to permit the slides and levers to move and perform their functions without interfering with each other.

From the foregoing description the operation of my improved voting-machine will be 45 readily understood. Hence to avoid repetition only a brief continuous description of the operation will be given.

The voter enters the door 6 of the booth, and if desirous of voting a straight ticket he 50 presses the lever 57, located directly above the emblem of the straight ticket which he desires to vote. This action forces the push-key 18 inwardly, actuates its crank-arm 39, turns a rock-shaft 40 and all the dogs 41 mounted thereon, and actuates a series of levers 21, whose arms 21^e are engaged by the said dogs. The arms 21^a of these levers 21 engage feet 16^a of the counting-registers 6, actuating the latter by virtue of the construction and arrangement of parts heretofore described. As the levers 21 are operated their arms 21^d engage the slides 19 and shift said slides toward the left, (see Fig. 19,) causing them to engage the notches 17^a of the push-keys 17 corresponding with the ticket voted 65 and the shoulders 17^d of all the other keys 17. This movement of the slides 19 throws the lever

42 to the dotted-line position in Fig. 19 and shifts the locking-slide 19^a of the straight-ticket push-keys, causing the said slide to engage the notch 18^a of the actuated key 18 and the shoulders 18^d on the inner extremities of all the other push-keys 18. As the slides 19 are moved toward the left their projections 19^e are engaged by the dogs 25, which lock 70 the said slides in the shifted position. This locking of the slides 19 also locks the lever 42 and the slide 19^a in the shifted position or that shown by dotted lines in Fig. 19. Hence it is now impossible to move any other push-key of the machine until the voter leaves the booth. If, on the contrary, he desires to vote a mixed ticket—that is to say, for one or more candidates on the several tickets—he presses a push-key 17 for every candidate, and as 80 fast as he presses the push-keys he locks all the other push-keys adjacent the names of candidates for the same office on all the tickets, the actuated push-key being at the same time locked at its inward limit of movement, 85 (thus preventing voting more than once for one candidate,) all by virtue of the construction heretofore fully explained. When the first individual push-key is pressed, the lever 42 is actuated and the slide 19^a moved to a position locking all the straight-ticket push-keys, and these remain locked, thus preventing the movement of individual and straight-ticket push-keys by the same voter. As the voter leaves the booth and swings the exit-door 7 outwardly the movement of the rod 34 turns the shaft 32 and brings the dog 31 in engagement with the lug 33 on the rod 30 and actuates the latter sufficiently to disengage the dogs 25 from the teeth 19^e of the 90 slides 19, thus releasing the slides and permitting them, together with the push-keys and other mechanism, to return to their normal position. The exit-door is then closed through the instrumentality of the automatic 95 door-closing mechanism 37, after which the machine is ready for the next voter.

By virtue of the well-known construction of the counting-registers the vote-registering operation is not complete until the locking-slides are released and the pressure-fee on the registers allowed to return to their normal position. Hence the complete registration of the vote can only be effected by opening the exit-door of the booth, as is necessary 100 as the voter passes out.

The push-keys 17 and 18 are provided with recesses 17^b and 18^b, respectively, into which the tongue 45^d of the expansion-slides 45 project when the push-keys are thrust inwardly 115 in the act of voting. The tongues 45^d of these slides lie in the path of and are engaged by the wedge-shaped extremities of the push-keys as the latter are pressed inwardly in the act of voting. By virtue of this engagement 120 the slide 45 is expanded sufficiently to prevent the inward movement of another push-key controlled by the same slide. In order to allow the proper inward movement of the

push-keys, the recesses 17^h and 18^h are formed to allow the tongues 45^a to enter them. In the absence of these recesses the tongues would interfere with the movement of the keys.

5 The outer plates 8 and 13 of the case are held in place by hinged clasps A and B. (See Fig. 5.) There are two pairs of these clasps, and the extremities of each pair overlap each other on the ends of the case. These overlapping extremities are apertured to receive eyes mounted on the case, in which may be inserted detachable keys for holding the clasps in place.

Having thus described my invention, what

15 I claim—

1. In a voting-machine, the combination with a suitable case and counting-registers, of push-keys movably mounted on the case and projecting thereinto, each key being provided with a notch formed in its body portion, an integral slide apertured to receive a number of push-keys, levers actuated by said keys for operating the counting-registers and the said slide, whereby the latter is made to enter the notch of the working push-key, and moved to a position adjacent the inner extremities of the idle push-keys, and suitable means for locking the slide in the shifted position.

30 2. In a voting-machine, the combination with a suitable case and counting-registers, of an individual push-key mounted on the case and projecting thereinto, a bell-crank lever inclosed by the case, one arm of the lever being connected with the inner extremity of the push-key, while the other arm of the lever acts on the pressure-foot of a counting-register, and a push-key locking-slide, the lever being provided with a third arm for actuating this slide and the push-key being provided with a bevel-faced notch, which the slide engages.

35 3. In a voting-machine, the combination with a suitable case and counting-registers, of a number of individual push-keys corresponding with the number of candidates for the same office on the several tickets, said push-keys being provided with bevel-faced notches, a bell-crank lever connected with each push-key and adapted to act on a counting-register as the push-key is pressed, a locking-slide apertured to allow the push-keys to pass therethrough, each lever being provided with a third arm for actuating the slide, which is adapted to engage the notch of the actuated push-key and shoulders on the other push-keys, and suitable means for locking the slide in the shifted position.

40 4. In a voting-machine, the combination with a suitable case and counting-registers, of a series of individual push-keys corresponding with the number of candidates for the same office on the several tickets, said push-keys being provided with bevel-faced notches, a bell-crank lever connected with each push-key and adapted to act on a counting-register as the push-key is pressed, a locking-slide

apertured to allow all of the push-keys to pass therethrough, each lever being provided with a third arm for actuating the slide, which is adapted to engage the notch of the actuated push-key and shoulders on the other push-keys, and suitable means for locking the slide in the adjusted position.

45 5. In a voting-machine, the combination with a suitable case provided with counting-registers, of a series of individual push-keys for each set of candidates for the same office, said keys being adapted, when actuated, to move inwardly, a bell-crank lever connected with each push-key and adapted to engage a counting-register, an integral locking-slide apertured to receive each series of push-keys, said slide being engaged and operated by the lever connected with any one of any series of push-keys, said lever being provided with a third arm for operating the locking-slide, means for locking each slide in the adjusted position, and means for releasing the locking-slides.

50 6. The combination with a booth and a suitable case located therein and equipped with counting-registers, of a series of individual push-keys for each candidate for the same office, a bell-crank lever connected with each push-key and adapted to engage the pressure-foot of a counting-register, a locking-slide for each series of push-keys, each slide being adapted to move independently of the other slides, each lever in any series being provided with an arm to actuate the corresponding slide as a push-key is pressed, the push-keys being provided with bevel-faced notches, the locking-slide being adapted to engage the notch of the actuated push-key, means for locking the slides in the adjusted position, and means operated from the exit-door of the booth for releasing the slides from the locking mechanism.

55 7. In a voting-machine, the combination with a suitable case equipped with counting-registers, of a series of individual push-keys for each set of candidates for the same office on the several tickets and a single straight-ticket push-key for each ticket, a lever connected with each individual push-key and adapted to act on a counting-register, suitable means operated by a straight-ticket push-key for actuating all the levers connected with the individual push-keys for all the candidates on any ticket, an integral locking-slide 19 for each series of individual push-keys corresponding with all the candidates for the same office on the several tickets, each slide being capable of operation independently of any other corresponding slide, a locking-slide 19^a for the series of straight-ticket push-keys, and a suitable connection between said slide and each slide 19, whereby the slide 19^a is actuated by the movement of any slide 19, said connection comprising a lever, fulcrumed on the case, one arm being connected with the slide 19^a and the other arm with a number of slides 19, which are arranged one

above another, and slotted to receive a screw-pin, which is fast in the lever, said screw-pin normally engaging one extremity of each slot.

8. In a voting-machine, the combination with a suitable case equipped with counting-registers, of a series of individual push-keys for each set of candidates for the same office on the several tickets and a single straight-ticket push-key for each ticket, a lever connected with each individual push-key and adapted to act on a counting-register, suitable means operated by a straight-ticket push-key for actuating all the levers connected with the individual push-keys for all the candidates on any ticket, said means comprising a rock-shaft and dogs mounted thereon, the dogs being arranged to engage the individual push-key levers, and the rock-shaft being connected with a straight-ticket push-key, an integral locking-slide 19 for each series of individual push-keys corresponding with all the candidates for the same office on the several tickets, each slide being capable of operation independently of any other corresponding slide, a locking-slide for the series of straight-ticket push-keys, a suitable connection between each slide 19^a and each slide 19, whereby the slide 19^a is actuated by the movement of any slide 19, said means comprising a lever fulcrumed on the case, one arm being connected with the slide 19^a and the other arm with a number of slides 19, which are arranged one above another and slotted to receive a screw-pin, which is fast in the lever, said screw-pin normally engaging one extremity of each slot, and means for locking the slides 19 in the adjusted position.

9. In a voting-machine and booth, the combination with a suitable case equipped with counting-registers, of a series of individual push-keys for each set of candidates for the same office on the several tickets and a single straight-ticket push-key for each ticket, a lever connected with each individual push-key and adapted to act on a counting-register, suitable means operated by a straight-ticket push-key for actuating all the levers connected with the individual push-keys for all the candidates on any ticket, a locking-slide 19 for each series of individual push-keys corresponding with all the candidates for the same office on the several tickets, each slide being capable of operation independently of any other corresponding slide, a locking-slide 19^a for the series of straight-ticket push-keys, a suitable connection between said slide 19^a and each slide 19, whereby the slide 19^a is actuated by the movement of any slide 19, means for locking the slides 19 in the adjusted position, comprising dogs adapted to engage projections formed on the slide extremities, and means operated from the exit-door of the booth for releasing the slides 19, said means comprising a rock-shaft, arms made fast to the rock-shaft, a transverse rod mounted on said arms and a rod connected with the transverse

rod at one extremity and with the door of the booth at the opposite extremity.

10. In a voting-machine and booth, the combination with a suitable case equipped with counting-registers, of a series of individual push-keys for each set of candidates for the same office on the several tickets and a single straight-ticket push-key for each ticket, a lever connected with each individual push-key and adapted to act on a counting-register, suitable means operated by a straight-ticket push-key for actuating all the levers connected with the individual push-keys for all the candidates on any ticket, an integral locking-slide 19 for each series of individual push-keys corresponding with all the candidates for the same office on the several tickets, each slide being capable of operation independently of any other corresponding slide, an integral locking-slide 19^a for the series of straight-ticket push-keys, a suitable connection between said slide and each slide 19, whereby the slide 19^a is actuated by the movement of any slide 19, said connection comprising a lever fulcrumed on the case, one arm being connected with the slide 19^a and the other arm with a number of slides 19, which are arranged one above another and slotted to receive a screw-pin, which is fast in the lever, said screw-pin normally engaging one extremity of each slot, means for locking the slides 19 in the adjusted position, means operated from the exit-door of the booth for releasing the slides 19, and suitable means for returning the slides to their normal position.

11. In a voting-machine and booth, the combination with a suitable case equipped with counting-registers, of a series of individual push-keys for each set of candidates for the same office on the several tickets and a single straight-ticket push-key for each ticket, a lever connected with each individual push-key and adapted to act on a counting-register, suitable means operated by a straight-ticket push-key for actuating all the levers connected with the individual push-keys for all the candidates on any ticket, a locking-slide 19 for each series of individual push-keys corresponding with all the candidates for the same office on the several tickets, each slide being capable of operation independently of any other corresponding slide, a locking-slide 19^a for the series of straight-ticket push-keys, a suitable connection between said slide and each slide 19, said connection comprising a lever fulcrumed on the case, one arm being connected with the slide 19^a and the other arm with a number of slides 19, which are arranged one above another and slotted to receive a screw-pin, which is fast in the lever, said screw-pin normally engaging one extremity of each slot, spring-held dogs engaging the slides 19 and holding them in the adjusted position, said dogs being provided with arms, a movable device located within the case and in whose path all the arms of the said dogs

are located, a rod connected with said device, and mechanism operated from the exit-door of the booth for actuating the said rod and disengaging the dogs from the slides 19.

- 5 12. In a voting-machine and booth, the combination with a suitable case equipped with counting-registers, of a series of individual push-keys for each set of candidates for the same office on the several tickets and a single straight-ticket push-key for each ticket, a lever connected with each individual push-key and adapted to act on a counting-register, suitable means operated by a straight-ticket push-key for actuating all the levers connected with the individual push-keys for each set of candidates for any ticket, a locking-slide 19 for each series of individual push-keys corresponding with all the candidates for the same office on the several tickets, each slide being capable of operation independently of any other corresponding slide, a locking-slide 19^a for the series of straight-ticket push-keys, a suitable connection between said slide and each slide 19, whereby the slide 19^a is actuated by the movement of any slide 19, said connection comprising a lever fulcrumed on the case, one arm being connected with the slide 19^a and the other arm with a number of slides 19, which are slotted to receive 30 a screw-pin, which is fast in the lever, said screw-pin normally engaging one extremity of each slot, spring-held dogs engaging the slides 19 and holding them in the adjusted position, said dogs being provided with arms, 35 a movable device located within the case and in whose path all the arms of the said dogs are located, a rod connected with said device, and mechanism operated from the exit-door of the booth for actuating the said rod and 40 disengaging the dogs from the slides 19, said mechanism comprising a rock-shaft mounted on the booth adjacent the exit-door, and a dog mounted on said shaft and adapted to engage a lug with which the rod is provided.
- 45 13. The combination with a suitable case and counting-registers, of a series of push-keys projecting into the case, a number of levers, each provided with three arms, one of which is engaged by a push-key, while another 50 acts on a counting-register, a push-key locking-slide actuated by the third arm of any lever, and an auxiliary expansion locking-slide adapted to be actuated by any push-key of the series, whereby it becomes impossible 55 to actuate more than one push-key of the series at the same time.

14. The combination with a suitable case and counting-registers, of a series of push-keys projecting into the case, a number of levers, each provided with three arms, one of which is engaged by a push-key, while another acts on a counting-register, a push-key locking-slide actuated by the third arm of any lever, the push-keys being provided with 60 wedge-shaped inner extremities, and an auxiliary expansion locking-slide, composed of sections and having limited endwise move-

ment, said sections having semicircular terminals which normally engage each other and form openings for the push-keys, each terminal having an inwardly-projecting tongue which is engaged by the wedge of the push-key, said key being provided with recesses which the tongues enter when the push-key is thrust inwardly, whereby, as any push-key is pressed, the slide is expanded only sufficiently to allow the single key to perform its function, thus preventing the simultaneous operation of several push-keys of the same series. 80

15. The combination with a suitable case and counting-registers, of a series of push-keys projecting into the case, a number of levers, each provided with three arms, one of which is engaged by a push-key, while another acts on a counting-register, an integral push-key locking-slide actuated by the third arm of any lever, said keys being provided with wedge-shaped inner extremities, an auxiliary expansion-slide composed of sections, stop-blocks provided with springs which the extremities of said slide engage, whereby the expansion or endwise movement of the slide is limited and the parts returned to their normal position when released, said slide having terminals which normally engage each other, any two terminals inclosing an opening for the entrance of the wedge of a push-key, whereby, as any push-key is pressed, the slide is expanded 90 only sufficiently to allow that key to perform its function, thus preventing the simultaneous operation of more than one push-key of the same series. 95

16. The combination with a suitable case and counting-registers, of push-keys mounted on the case and projecting thereinto, an integral push-key locking-slide apertured to receive the push-keys which are formed with notches, their inner extremities being provided with wedges and shoulders at the base of the wedges, levers, each provided with three arms, one connected with the push-key, another engaging a counting-register, while the third actuates the locking-slide, and an auxiliary expansion-slide actuated by the wedges of the push-keys to prevent the simultaneous operation of a number of push-keys. 110

17. In a voting-machine, the combination with a suitable case and counting-registers, of a push-key mounted on the case and projecting thereinto, a lever inclosed by the case, one arm of the lever engaging the inner extremity of the push-key, while the other arm of the lever acts on a counting-register, a push-key locking-slide actuated by the lever and engaged by an inclined face formed on the key, whereby, as the latter is returned to its normal position, it imparts the reverse movement to the slide. 115

18. In a voting-machine, the combination with a suitable case equipped with counting-registers, of a series of individual push-keys for all the candidates for the same office on

- the several tickets and a single straight-ticket push-key for each ticket, a lever connected with each individual push-key and adapted to act on a counting-register, a rock-shaft, dogs mounted in the shaft and adapted to engage the levers as the shaft is operated, a crank-arm fast on the shaft, a link connecting the straight-ticket push-key with the crank-arm, a locking-slide 19 for each series of individual push-keys, a locking-slide 19^a for the series of straight-ticket push-keys, and a connection between the slide 19^a and all the slides 19, whereby the movement of any slide 19 actuates the slide 19^a, said connection comprising a lever fulcrumed on the case, one arm being connected with the slide 19^a and the other arm with the slides 19 which are slotted to receive a screw-pin, which is fast in the lever.
20. In a voting-machine, the combination with a suitable case and counting-registers, of a series of straight-ticket push-keys provided with notches, a series of individual push-keys notched on the side opposite the notches of the straight-ticket push-keys, an integral locking-slide apertured to receive the straight-ticket push-keys, a separate integral locking-slide apertured to receive the individual push-keys, a lever connecting the two slides, means actuated by the push-keys for operating the counting-registers and shifting the individual push-key locking-slide whereby the said lever is actuated and the straight-ticket-push-key locking-slide shifted 35 in the opposite direction, the notch of the actuated push key or keys being engaged by their corresponding locking-slides.
20. In a voting-machine, the combination with a suitable case and counting-registers, 40 of a series of push-keys for operating the counting-registers, each key being provided with a notch, an integral locking-slide apertured to receive the keys, and levers, one of which is actuated by any push-key of the series for shifting the locking-slide, whereby it is made to engage the notch of the actuated push-key and move to a position adjacent the inner extremity of the other push-keys, whereby all the push-keys of the series are 45 locked from movement.

21. In a voting-machine, the combination with a suitable case and counting-registers, of a series of notched push-keys mounted on the case and adapted to project thereinto, an integral push-key locking-slide apertured to receive the push-keys, an auxiliary endwise-expansible locking-slide composed of sections and located to the rear of, but in line with the integral locking-slide, the sections of the auxiliary slide having semicircular terminals 55 which normally engage each other and form openings for the entrance of the push-keys, the expansion of the slide being only sufficient to permit the entrance of a single push-key at one time, levers located within the case, each lever being provided with three arms, one being connected with a push-key, another engaging a counting-register, while the third projects through an opening formed in a section of the expansive slide to engage- 60 ment with the integral locking-slide.

22. In a voting-machine, the combination with a suitable case and counting-registers, of a series of straight-ticket push-keys and a number of series of individual push-keys, a locking-slide 19^a for the series of straight-ticket push-keys and a locking-slide 19 for each series of individual push-keys, a lever fulcrumed on the case and having one arm connected with the locking-slide 19^a and the other arm connected with the several locking-slides 19, the slides 19 being slotted to receive a pin fast in the lever, whereby the movement of any one of the slides 19 actuates the lever and moves the slide 19^a in the opposite 85 direction, a spring engaging the lever and acting to return it and the slide 19^a to their normal position, means actuated by any push-key for operating the counting-registers and one or more slides 19, whereby the lever 90 and the slide 19^a are actuated, thus locking the straight-ticket push-keys and one or more of the series of individual push-keys.

In testimony whereof I affix my signature in presence of two witnesses.

GEORGE W. TROMMLITZ.
